UNITED STATES PATENT OFFICE

PAUL K. CRAMBLETT, OF MILWAUKEE, WISCONSIN, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

MERCURY SWITCH

Application filed December 7, 1928. Serial No. 324,494.

This invention relates in general to mercury switches and more particularly to a novel protective casing and mounting for mercury switches and to a method of making the same.

Mercury switches usually have an outer envelope of soft glass which is advantageous in that it is comparatively inexpensive and easily worked. Other materials have been proposed and in some instances used but they are either too expensive or too difficult to work or else have some other serious disadvantage. The sole disadvantage of the soft glass outer envelope so widely employed is its 15 fragility, as a result of which it is liable to and frequently does become broken or cracked when subjected to the usage of actual practice. If the envelope of the switch becomes cracked or broken its operativeness is at once impaired not only because of the loss of the mechanical strength and structure of the outer envelope but also because the atmosphere of hydrogen or other inert gas essential to efficient switch operation is lost, 20 and, if the crack becomes pronounced, there is loss of the mercury.

The present invention proposes the provision of a protective casing or covering for the outer envelope of the switch which is elastic 30 or resilient so as to absorb and distribute shocks or strains which would ordinarily be applied to the envelope and concentrated upon a small portion thereof and result in cracking or breaking. Further, the covering is impervious to the air or gas and so it hermetically seals the mercury switch within it. As a consequence even though the envelope be cracked the protective casing maintains the structural integrity and mechanical 35 strength of the switch and prevents loss of the inert gas or of the mercury.

Another object of the invention is to provide a protective covering of this character 40 which facilitates the mounting of the switch and the operation thereof and which relieves the envelope of the switch of concentrated strain due to its mounting or operation, the strains of mounting and operation being largely absorbed and such stress as is applied

to the glass envelope being distributed over the entire area thereof.

Another object of the invention is to provide a protective covering having these advantages and capacities and which makes it possible to provide a mercury switch with completely sealed and insulated supply conductors, whereby the mercury switch may be immersed and operated in a fluid and completely protected and insulated therefrom.

Other objects and advantages reside in certain novel features of the construction, arrangement and combination of parts which will be hereinafter more fully described and particularly pointed out in the appended claims, reference being had to the accompanying drawings, forming a part of this specification, and in which:

Figure 1 is a view in central longitudinal vertical cross section showing a mercury 70 switch equipped with a protective covering embodying the present invention;

Figure 2 is a view thereof in cross section taken on line 2—2 of Figure 1;

Figure 3 is a view similar to Figure 1 but 75 showing another form of the invention;

Figure 4 is a view in cross section taken on line 4—4 of Figure 3;

Figure 5 is a view in side elevation illustrating one mode of mounting and operating 80 the switch; and

Figure 6 is a sectional view taken in the plane of line 4—4 of Figure 3 and illustrating how this switch construction can be organized with completely insulated supply 85 conductors.

Referring to the drawings, and more particularly to Figures 1 and 2, the numeral 1 designates generally a mercury switch which may be of any suitable construction. The 90 particular switch shown is selected merely for the purposes of illustration and, of course, any type of mercury switch may be utilized. For example, switches of the type having a mercury to mercury make and break may be 95 utilized. As illustrated, the mercury switch has an outer glass envelope 2 containing a body of mercury 3 and an atmosphere of inert gas. Electrodes 4 and 5 are sealed in through the envelope 2 and as the switch 100

is operated the mercury alternately makes and breaks the circuit across the electrodes 4 and 5 by bridging these electrodes in one position of the switch and by flowing away 5 from and out of contact with the electrode 5 in the other position of the switch.

The present invention proposes to enclose and seal the outer envelope 2 in a covering or casing of rubber, designated at 6, the rubber completely surrounding the envelope and 10 also portions at least of the electrodes 4 and 5 which lead thereinto.

In the form of the invention shown in Figure 3, a mercury switch is designated 15 generally at 10 and has an outer soft glass envelope 11 through which electrodes 12 and 13 are sealed. The switch also contains a body of mercury 14 which operates to make and break the electrical circuit when the 20 switch is operated. The particular manner in which the mercury accomplishes this is immaterial to the present invention, as the present invention is applicable to all the various methods and structures that have been 25 proposed in mercury switches for effecting this switch operation. As is conventional, the envelope contains an atmosphere of inert gas, such as hydrogen, which suppresses arcing.

As in the embodiment of the invention first 30 described, the envelope 10 is enclosed or embedded in a covering or casing of rubber designated at 15. In this form of the invention the portions of the electrode 12 and 13 projecting outside of the envelope 11 and the 35 flexible leads 16 and 17 connected thereto, are all completely and entirely embedded in the body of the rubber covering 15. At the opposite sides of its center, the rubber casing 15 is provided with integral laterally extending 40 mounting lugs 18, having centrally located apertures 19 lined with flanged bushings 20 of material that is a good conductor of electricity. The leads 16 and 17 are electrically connected with these bushings 20 and 45 the external circuit is connected to the bushings 20 in any suitable manner.

The lugs 18 are adapted to co-act with any appropriate form of mounting. In Figure 5 an illustrative example of the mounting is 50 shown at 25 and the lugs are secured to this mounting in any suitable manner as by means of nuts 25' threaded on the mounting and clamping the lugs 18 between them. This enables the switch to be oscillated by alternately exerting pressure upon one end of the 55 switch and relieving it of such pressure. Thus, as shown in Figure 5, an operating arm 26 fixed on a rocking or oscillating shaft 26' may be provided to periodically press down 60 on one end of the switch thereby tilting the switch due to the flexion of its lugs 18. The inherent elasticity of the lugs 18 returns the switch automatically to its normal position as soon as the pressure exerted by the arm 26 65 is relieved.

As will be understood from the foregoing and from a consideration of Figures 4 and 5, this construction avoids all exposed leads and it may be readily adapted to a construction which is associated with completely insulated lead-in supply conductors. Thus, as 70 shown in Figure 6, a combined mounting and supply conductor designated generally at 27 is provided for each mounting lug and is encased in an insulating cover 28 except for 75 the portion thereof that projects into the bushing 20 and engages the nuts 25'. The exposed portions of the bushings 20, nuts 25' and combined mountings and supply conductors 27 are covered by applying gum rubber thereto as indicated at 29 after the assembly 80 has been completed.

The rubber covering or casing may be applied to the mercury switch in either of the foregoing embodiments in various ways 85 which are well known to those skilled in the art of rubber. But a highly effective and preferred method of producing a protected switch of this character is to take the completely constructed conventional mercury 90 switch and first dip it into gum rubber and then allow it to set. Several dippings and dryings may be resorted to, if desired, but usually one is sufficient. After the dipping in gum rubber the coated tube is placed in a soaped mold. The mold is then closed and a plastic rubber compound is forced into the mold to completely surround the coated mercury switch and the portions of its electrodes or all of its electrodes, as desired. Finally, 100 the assembly is subjected to heat to cure the rubber and effect vulcanization.

Another method is to take the tube after it has been coated with the gum rubber and place it on a sheet of soft plastic rubber contained in one section of the mold. Another sheet of similar rubber is placed in the other section of the mold and then the mold sections are brought together to cause the sheets to encompass the switch and to squeeze out 110 the excess of rubber. With the mold sections secured together the assembly is subjected to heat to effect curing and vulcanizing of the rubber. Either of these methods 115 may be practiced without the prior dipping in the gum rubber but the dipping in the gum rubber while not essential for all purposes is preferable as it greatly increases the impermeability of the protective casing to air and gas and makes it possible for the switch to stand up over a long period of time even if the glass envelope thereof has been cracked.

It is to be understood that while one form of mounting means is shown, various forms 125 may be utilized. The structure shown in Figure 1 is particularly adapted for use with mountings employing resilient clips or grippers. Any form of mounting that is utilized may firmly grip the switch and yet 130

the gripping pressure is distributed over the whole tube through the elastic casing.

Where a mounting of the type shown in Figure 2 is employed the mounting takes part in the operation of the switch, as above pointed out, for the inherent resiliency of the lugs automatically return the switch to normal position after each positive actuation thereof by the operating means. Further, the protective casing protects the tube against breakage by distributing or absorbing shocks or strains. Finally, as pointed out, even in the event of breakage of the outer envelope the protective casing preserves the mechanical strength and structure of the switch and prevents loss of its arc suppressing gas or loss of its mercury.

While the covering or casing is preferably constituted of rubber, it is obvious that it may be made up of any suitable material having the requisite elasticity and the property of being impervious to air and gas.

The invention claimed is:

1. In combination, a mercury switch having electrodes, flexible leads connected to the electrodes of the switch, and a covering of elastic rubber completely surrounding the switch, the electrodes and the leads to protect and hermetically seal the same, said covering having integral mounting lugs.

2. In combination, a mercury switch, flexible leads connected to the electrodes of the switch, and a covering of elastic rubber completely surrounding the switch, the electrodes and the leads to protect and hermetically seal the same, said covering having integral mounting lugs, said mounting lugs having electrical connectors embedded therein and connected to the flexible leads.

3. In combination, a mercury switch and an elastic rubber covering completely encasing the switch and hermetically sealing the same and having integral mounting means adapted to co-act with the mounting to support the switch and to bias the same to a normal position.

4. In combination, a mercury switch and an elastic covering completely encasing the switch and hermetically sealing the same, and having integral lugs formed with bushed openings adapted to co-act with supporting means and electrical supply conductors.

5. In combination, a mercury switch and an elastic covering completely encasing the switch and hermetically sealing the same, and having integral lugs formed with bushed openings adapted to co-act with supporting means and electrical supply conductors, and flexible leads embedded in the covering and extending from the bushings to the electrodes of the switch.

6. In combination, a mercury switch having an outer glass envelope and electrodes sealed therethrough, an elastic covering completely encasing the switch and hermetically

sealing the same, said elastic casing having integral resilient mounting members formed with electrical conducting means connected to the electrodes of the switch, insulated supporting means and electrical supply conductors co-acting with the mounting members and the electric conducting means thereof, and a covering of insulating material for the connected portions of said mounting members and said supporting means and electrical supply conductors.

7. In combination, a mercury switch, an elastic covering therefor having elastic mounting members supporting the switch and biasing the same to one position, and means for periodically displacing the switch to another position against the biasing action of the mounting members.

In witness whereof, I hereto affix my signature.

PAUL K. CRAMBLETT.
